(57) **CLAIM**

The ornamental design for a stadium chair, as shown and described.

DESCRIPTION

FIG. 1 is an isometric view of a stadium chair showing our new design;

FIG. 2 is a top plan view of the stadium chair of FIG. 1;
FIG. 3 is a back elevation view of the stadium chair of FIG. 1;
FIG. 4 is a left side elevation view of the stadium chair of FIG. 1;

FIG. 5 is a front elevation view of the stadium chair of FIG. 1;
FIG. 6 is a right side elevation view of the stadium chair of FIG. 1; and,

FIG. 7 is a bottom plan view of the stadium chair of FIG. 1. In the drawings, the broken lines in FIGS. 1-7 depict portions of the design that form no part of the claim.
